UNITED STATES PATENT OFFICE.

THOMAS PORTER, DECEASED, BY NELLIE PORTER, ADMINISTRATRIX, OF MIFFLIN TOWNSHIP, ALLEGHENY COUNTY, PENNSYLVANIA.

FALSE SILL FOR OPEN-HEARTH-FURNACE DOORS.

1,399,516.

Specification of Letters Patent. Patented Dec. 6, 1921.

Application filed January 10, 1921. Serial No. 436,151.

To all whom it may concern:

Be it known that THOMAS PORTER, deceased, did invent certain new and useful Improvements in False Sills for Open-
5 Hearth-Furnace Doors, of which the following is a specification.

This invention relates to a false sill for open hearth furnaces, and particularly to a false sill for use with the charging door of
10 such furnaces.

The invention consists of a cast iron member so constructed that it can be put in place on the permanent door sill, and removed by means of the charging machine peel. The
15 sill is used when charging hot metal into the furnace to prevent the metal from splashing or overflowing through the door until the heat has settled itself, thus eliminating the danger of burns to workmen.

20 Heretofore, door sills of open hearth furnaces have been built up in different ways. One of which has become common, is the use of a pig of iron which was manually lifted and set in position. However, nothing used
25 heretofore had the advantages of the present invention, which may be lifted into place by the peel of the charging machine, which is of such shape and size as to form a perfect fit with the permanent sill, and which is of sufficient height to form a support for the hot metal spout.

30 Referring to the drawings, Figure 1 is a side elevation of a portion of an open hearth furnace, showing the false sill in position.

35 Fig. 2 is a vertical section on the line II—II of Fig. 1, showing the hot metal spout in position to discharge the hot metal.

Fig. 3 is a top plan of the sill.

Fig. 4 is a front elevation thereof.

40 Fig. 5 is a cross section on the line V—V of Fig. 4.

45 Referring more particularly to the drawings, the letter A designates the open hearth furnace as a whole, which has a charging door opening 2 provided with a permanent rigid metallic sill 3.

50 The false sill constructed in accordance with this invention is designated as a whole by the letter B, and comprises a substantially rectangular body of cast iron or the like having its front face beveled off adjacent each end, forming a projection or head portion 4.

55 A substantially rectangular recess 5 is cut in the head portion 4, and opens through the front face of the head. The recess 5 is en-

larged to a greater width for a substantial distance from the front face of the head forming shoulder projections 6 and 7 which are flared or beveled at their tops to facilitate the entrance or guide the flanged front 60 end of the charging peel 9 of a charging machine (not shown). The end of the charging peel 9 is rectangular in outline and is made to fit within the recess 5, so that the sill may be readily handled by the peel. A locking 65 bolt 10 is slidably mounted within the charging peel and is adapted to enter an opening or recess 11 in the rear face of the recess 5 to lock the sill on the peel when it is being placed in position.

70

The sill B is of slightly greater width than the doorway 2, and is adapted to abut the outer faces of the side walls thereof, and to firmly rest upon the permanent rigid sill 3.

75 After the sill B is placed in position, the furnace is banked up so as to provide an even and continuous inclined surface from the plane of the upper face of the sill.

When the furnace is ready to receive the charge of molten metal the hot metal spout 80 Y will be positioned so as to rest upon and be supported by the false sill B.

85 It will be readily seen that by the use of the false sill the capacity of a furnace may be greatly increased without changing its construction.

90 It will also be seen that the danger of splashing out or running over of the metal is reduced to a minimum, and therefore, the sill acts as a safeguard for the workers.

95 What is claimed is—

1. A false sill as and for the purpose described, comprising a substantially rectangular body portion, and a projecting head portion having a recess therein for the reception of the peel of a charging machine.

100 2. The combination of an open hearth furnace having a charging door, of a false sill adapted to be detachably mounted in said doorway, said sill comprising a substantially rectangular body portion, and a projecting head portion having a recess therein for the reception of the peel of a charging machine, substantially as shown and described.

105 3. The combination of an open hearth furnace having a charging door, of a false sill adapted to be detachably mounted in said doorway, said sill comprising a substantially rectangular body portion having its forward face beveled at each end forming a project- 110

ing head portion, said head portion being provided with a recess for the reception of the peel of a charging machine, said recess being enlarged a substantial distance from the forward face of said head forming shoulders adapted to engage the peel and hold it in position, said shoulders having their up- per faces beveled to guide the peel into said recess.

In witness whereof, I have hereunto signed my name.

NELLIE PORTER.
*Administratrix of the estate of Thomas
Porter, deceased.*
